UNITED STATES PATENT OFFICE.

JOSEPH N. LOVELEY, OF DETROIT, MICHIGAN.

REINFORCING-BAR.

No. 889,249.

Specification of Letters Patent.

Patented June 2, 1908.

Application filed June 25, 1907. Serial No. 380,716.

To all whom it may concern:

Be it known that I, JOSEPH N. LOVELEY, a citizen of the United States, residing at Detroit, in the county of Wayne, and State 5 of Michigan, have invented certain new and useful Improvements in Reinforcing-Bars, of which the following is a specification.

This invention is a structural metal beam or bar for use as a reinforcement in concrete 10 building construction, and has for its object to provide a strong and rigid reinforcement which will not slip when molded in the beam or building element, the bar being provided with projecting ribs or lugs which engage 15 the concrete and assist in binding the same to the material in which it is embedded.

The invention is illustrated in the accompanying drawings, in which

Figure 1 is a side elevation of the bar. 20 Fig. 2 is a top plan view. Fig. 3 is an end view. Fig. 4 is an end view of a modification. Figs. 5, 6, 7 and 8 are corresponding views of a different form, having projecting lugs instead of ribs.

The body 6 of the bar is rolled to an angular, folded or flanged shape, the form for example either a **V** bar, as shown in Figs. 3 and 25 7, or a **U**, as shown in Figs. 4 and 8. These forms are believed to produce a more rigid reinforcement than a round or square bar, with the same or a less amount of stock, and also afford more surface for the contact and adhesion of the concrete in which the bar 30 will be embedded.

In one form, as shown in Figs. 1 to 4 inclusive, the inner and outer or opposite surfaces of the bar are provided with cross ribs 35 7 which project from said surfaces, say about one-eighth of an inch. There is a series of 40 these ribs, which may be located opposite to each other on the opposite sides of the bar. The edges of the bar are provided with projecting lugs 8 which may be conveniently located at the spaces between the ends of the

ribs, and these lugs project in the same plane 45 as the flanges of the bar.

In another form, as shown in Figs. 5 to 8, inclusive, the opposite surfaces of the bar have sets of projecting lugs or interrupted ribs 9, which may project about one-eighth of 50 an inch above said surfaces. These lugs are arranged in a series of lines across the bar, and are spaced from each other, and the lugs of the alternate rows are staggered with respect to each other. That is, the lugs of one 55 row are in line with the spaces of the adjacent row. This form may also have the projecting lugs 8 at the edge, as shown.

The projecting ribs or lugs prevent any draw or slip of the reinforcement in the beam 60 under weight or strain, since when the concrete hardens it engages said projecting ribs or lugs, or the shoulders formed thereby and prevents slip in any direction. The bar will preferably be rolled or produced in steel and 65 the shapes indicated give great strength and resistance to both bending and torsional strains.

I claim:

1. A bar adapted for use as a concrete reinforcement, comprising a flanged shape or body opposite faces of which have a series of spaced projections extending transversely across the same and spaced projections at the edges of the flanges. 70

2. A bar adapted for use as a concrete reinforcement, comprising a body having opposite longitudinal flanges provided with spaced ribs extending crosswise on both sides thereof and lugs projecting at the edges of 75 80 the flanges.

In testimony whereof I affix my signature, in presence of two witnesses.

JOSEPH N. LOVELEY.
